UNITED STATES PATENT OFFICE.

GUSTAV FUSCH, OF HANOVER, GERMANY.

METHOD OF ATOMIZING SOLID MEDICAMENTS.

No. 928,038.

Specification of Letters Patent.

Patented July 13, 1909.

Application filed December 8, 1908. Serial No. 466,436.

To all whom it may concern:

Be it known that I, GUSTAV FUSCH, a subject of the Emperor of Germany, residing in Hanover, Germany, (whose post-office address is No. 2 Alleestrasse,) have invented certain new and useful Improvements in Methods of Atomizing Solid Medicaments, of which the following is a full, true, and concise specification.

10 The invention is a method of atomizing liquid solutions, and particularly medicinal solutions, for use in the treatment of disease by inhalation.

It has heretofore been customary to produce an atmosphere impregnated with finely divided atomized particles of the medicine by means of ordinary spray or atomizing nozzles which are operated within a closed treatment chamber wherein the patient is confined. In such cases, a large percentage of the medicine thus atomized is found to combine or condense into small drops, which are wasted, so that the intended separation and distribution of the solution does not take 25 place.

The present invention aims to increase the fineness and promote the dryness of the atomized spray so that the formation of the drops is avoided and the solid component 30 of the medicinal solution is converted into an extremely subdivided and practically dry dust-like condition, in which it is dispersed in the chamber. The treatment is thus more effectively and agreeably applied.

35 Figure 1 is a diagrammatic view of a form of apparatus adapted to carry on the new process, and Fig. 2 is a longitudinal sectional view of a spraying or atomizing instrument capable of use therewith.

40 The method consists in putting the liquid solution under pressure of the solid medicament before it reaches the spraying or atomizing instrument and also heating it to a temperature somewhat above its normal or 45 atmospheric boiling point, and preferably to a temperature approximating its boiling point at the pressure to which it is thus subjected, so that on issuing from its outlet in the atomizing instrument the pressure thereon is relieved and the excess of heat produces an instantaneous evaporation of the liquid. In this manner the atomized particles are relieved of the greater part, if not all, of their liquid and are converted into a dry 50 dust-like condition, especially suited for suspension in the atmosphere of the treating

chamber, as will be obvious to those skilled in this art. The extent of the pressure and the amount of heat applied to the liquid are the factors which control the dryness of the 60 produced spray and may be regulated or proportioned accordingly, having regard to the strength of the solution employed.

The method, as will be observed from the foregoing description, may be performed 65 with or by a variety of forms of apparatus. The drawing forming a part hereof illustrates, partly in diagram, a simple form of apparatus suited for the purpose.

The liquid solution from a receptacle 1 is 70 put under pressure by the pump 2 and conducted through a pipe 3 to a heating-coil 4 and thence to the atomizing instrument 5. The coil may be heated by any suitable means, and the atomizing instrument may 75 consist of any simple form of atomizing device. In one form of apparatus the said instrument comprises an inner nozzle 6 connected with the liquid pipe and provided with a somewhat restricted outlet. The 80 outer casing 7 serves as an outer nozzle, which is concentric to the inner nozzle and is connected by the pipe 8 to a source of compressed air, not shown. A spiral deflector 9 is disposed in the annular space between 85 the inner and outer nozzles, so that the air thereby receives a whirling motion, which tends to facilitate the expansion and dispersion of the sprayed particles, in a manner which will be apparent to those versed in 90 this art. As illustrated in the diagram of Fig. 1, the nozzles are shown for convenience as plain spray nozzles of any desired type not employing compressed air.

The liquid medicinal solution, say a saturated solution of sodium chlorid in water or nearly saturated is charged in the supply receptacle and put under pressure in the pipe 3 and its connections, wherein it is heated to a temperature above the normal 100 atmospheric boiling temperature of the particular solution, the pressure exerted by the pump being sufficient to prevent boiling of the solution within the pipe or heater coil. Upon passing through the spray-nozzles 5 105 the sudden relief of the pressure produces a violent and sudden ebullition of the liquid with consequent vaporization taking place while the liquid is in the process of dispersion under the effect of the atomizing instrument so that the moisture at first accompanying 110 the atomized particles is presently evap-

orated and the solid residue is launched into the air-treating room in a finely divided and very dry state.

I claim as my invention the following:—

- 5 1. A method of atomizing liquid solutions of a solid medicament, which consists in putting the said solution under pressure and heating it to a temperature above its boiling point in the atmosphere and then suddenly
- 10 relieving the pressure on said liquid while discharging it through an atomizing instrument, whereby the moisture of the solution is evaporated by the expansion and the solid residue of said solution is projected in a dry
- 15 impalpable state.

2. A method of atomizing liquid solutions of a solid medicament, which consists in put-

ting the said solution under pressure and heating it to a temperature approximating the boiling point of that liquid at the particular pressure and then relieving the said pressure while discharging the liquid through an atomizing instrument whereby the moisture of the solution is evaporated by the expansion and the solid residue of said solution is projected in a dry impalpable state.

In testimony whereof, I have signed my name to the specification in the presence of two subscribing witnesses.

GUSTAV FUSCH.
